(57) **CLAIM**

We claim the ornamental design for a bottle recycling machine, as shown and described.

DESCRIPTION

FIG. 1 is a front elevational view of a bottle recycling machine, showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a top front left perspective view thereof.
